DESIGN FOR A KNITTED FABRIC

Harry Moses, New York, N. Y.

Application January 11, 1938, Serial No. 74,198

Term of patent 3½ years

To all whom it may concern:

Be it known that I, Harry Moses, a citizen of the United States, residing at 809 West 177th Street, in the county of New York, city and State of New York, have invented a new, original, and ornamental Design for a Knitted Fabric, of which the following is a specification, reference being had to the accompanying drawing, constituting a part thereof.

The figure is a plan view of a piece of the knitted fabric showing my new design.

I claim:

The ornamental design for a knitted fabric, substantially as shown.

HARRY MOSES.
